UNITED STATES PATENT OFFICE.

OLIVER P. STRICKLER AND BURDETTE C. LEWIS, OF MASON CITY, IOWA, ASSIGNEES TO
WONDER CARBURETOR HEATER COMPANY, A CORPORATION OF IOWA.

CARBURETER-HEATING DEVICE.

1,230,619.

Specification of Letters Patent. Patented June 19, 1917.

Application filed October 25, 1916. Serial No. 127,633.

To all whom it may concern:

Be it known that we, OLIVER P. STRICKLER and BURDETTE C. LEWIS, citizens of the United States, residing at Mason City, in the 5 county of Cerro Gordo and State of Iowa, have invented certain new and useful Improvements in Carbureter-Heating Devices, of which the following is a specification.

This invention relates to certain new and 10 useful improvements in carbureter heating devices.

The primary object of the present invention is to provide a heating device for carbureters wherein the source of electricity 15 used for the lighting or starting systems of an automobile may be utilized in connection with an electric heater associated with the carbureter for purposes of heating the same to insure a gas vapor being formed in the 20 carbureter whereby the motor may be easily started.

A further object of the invention is to provide an electric heater for carbureters wherein the heating element is positioned directly 25 within the carbureter and in intimate contact with the bottom wall of the bowl thereof, whereby the gasoline or other fluid contained therein may be easily and quickly vaporized to insure an easy starting of the motor.

With these general objects in view and others that will appear as the nature of the invention is better understood, the same consists in the novel construction, combination and arrangement of parts hereinafter more 35 fully described, illustrated in the accompanying drawings, and then claimed.

In the drawings forming a part of this application and in which like designating characters refer to corresponding parts throughout the several views:

Figure 1 is a perspective view, partly in section, of a carbureter including a float with the present invention in operative position therein, and also illustrating an improved 45 form of switch plate upon the dash-board of a vehicle for purposes of controlling the source of electricity.

Fig. 2 is a sectional view on an enlarged scale of the heating element with a portion 50 of the same turned substantially at right angles from its operative position.

Fig. 3 is a side elevational view of the casing of the heating element.

Fig. 4 includes side and sectional views of

the insulator bushing associated with the 55 casing, and;

Fig. 5 is an elevational view of the contact plug removed from the bushing.

Briefly described, the present invention aims to provide an electric heating device 60 for carbureters especially adapted for use with automobiles wherein the resistance element is directly positioned within the carbureter and in intimate contact with the bottom wall thereof while a switch plate is 65 mounted upon the instrument board of the automobile and by which the electric current for the heating element is controlled. The heating element includes a casing threaded into an opening provided in the carbureter 70 while the inner end of the casing has connected thereto a metallic tubing preferably of malleable material so that the same may be caused to intimately engage the bottom wall of the carbureter. A resistance wire is 75 arranged within the tubing and supports a plurality of anti-friction members, as agate beads, whereby the resistance wire is held spaced from the tubing at all times. The resistance wire leads to the switch plate 80 which is in communication with a storage battery or dry cells of the automobile.

Referring more in detail to the accompanying drawing, the reference numeral 10 designates a carbureter including a float 11 and having a threaded plug 12 attached thereto by which the same is secured to the manifold of a gas engine. As shown in Fig. 1, the bottom of the carbureter 10 is provided with a pet cock 13 for purposes of 90 draining the bowl of the carburetor.

The improved form of heating device associated with the carbureter 10 is more clearly shown in Figs. 2 to 5 and includes a casing 14 having one end closed as at 15 with a lateral opening 16 arranged adjacent the closed end, the casing 14 having an annular flange 17 arranged adjacent the opening 16 while the portion of the casing opposite the flange 17 is screw-threaded as at 18 100 for threaded engagement with an opening provided in the lower end of the carbureter 10. When so positioned, the threaded end of the casing 14 projects outwardly of the carbureter 10 as shown in Fig. 2 and is adapted 105 for the reception of a lock nut 17, whereby the same may be locked in position, it being understood that packing elements as lead

washers 17^b may be positioned between the flange 17, nut 17^a and the wall of the carbureter. The threaded end of the casing 14 is entirely open and is adapted for the reception of the insulator bushing 19 having a shoulder 20 defining a reduced portion, and within which reduced portion there is provided a pair of diametrically opposite grooves 21. When the insulator bushing 19 is arranged within the open end of the casing 10, the shoulder 20 engages the outer end of the casing 14 and the grooves 20 provided therein register with similar grooves 22 provided in the outer end of the casing 14, and within which registering grooves are positioned retaining elements, as keys 23. A metallic terminal plug 24 is forcibly positioned within the bore of the insulator bushing 19, and as shown in Fig. 2, the terminal plug and insulator bushing are provided with co-operating shoulders which will limit the inward movement of the plug. As shown, the plug is of such length as to permit the inner end thereof projecting beyond the inner end of the bushing for purposes of attaching the resistance wire thereto.

The inner projecting end of the plug 24 is provided with a terminal opening 25 communicating with the transverse bore 26 and the resistance wire 27 has one end thereof introduced into the terminal bore 25 and laterally directed into the transverse bore 26 and retained in such position by the fastening pin 28. The resistance wire 27 is arranged within a metal tubing 29 which has one end extended into the opening 16 provided in the casing 14 while the other end of the tubing 29 is closed as by a metallic plug 30. The outer end of the resistance wire 27 is passed through an opening provided in the plug 30 and is adapted to be engaged by a wedge pin 31 for retaining the same in position. As shown in Fig. 2, the resistance wire 27 supports a plurality of beads 32 which may be of any known non-conducting material as agate, which will hold the resistance wire spaced from the tubing 29 to reduce friction and wear on the wire as well as damage which might be caused by short circuiting. The tubing 29 as shown in Fig. 2, has been twisted at right angles from its operative position for purposes of illustration and it is to be assumed that the tube is in the position shown in Fig. 1 when operatively arranged.

The outer projecting end of the terminal plug 24 has a threaded extension 33 adapted for the reception of a thumb nut 34 for clamping the metallic wire holder 35 thereto, the wire holder 35 carrying the wrapped wire 36 which extends to the rear of and is suitably connected to the switch plate 37 upon the instrument board 38 of an automobile. As shown in Fig. 1, the switch plate is provided with a hand switch 39, a light bulb

40 and a push button 41. When the switch 39 is turned to close a circuit, one-half of the source of electricity is thrown in circuit with the resistance wire 27, and simultaneously with the closing of the circuit, the light bulb 40 is illuminated to indicate that the device is properly circuiting. The current passes from the wire 27 to the plug 30 and tube 29 which is in intimate contact with the carbureter 10 for heating the contents thereof, as will be plainly obvious. It is to be understood that in extremely cold weather, the switch 39 may be left turned on to feed the resistance wire with one-half of the current should the automobile be left standing for a long period. By operating the push button 41, the entire current is thrown in with the resistance wire 27 and tubing 29 and practically in one minute, the contents of the carbureter may be heated to such an extent as to insure a ready and easy starting of the motor.

From the above detailed description of the invention, it is thought that the construction and operation thereof is readily apparent and while the form of the invention herein shown and described is what is believed to be the preferred embodiment thereof, it is nevertheless to be understood that various forms, modifications and arrangements of the parts may be made without departing from the spirit and scope of the invention as claimed.

What we claim as new is:

1. A heater for carbureters comprising a casing, an insulator bushing therein, a plug within the bushing, a tubing carried by the casing and closed at one end, a resistance wire within the tube and connected to the closed end thereof and to said plug, and agate beads carried by the wire to hold the same spaced from the tubing.

2. A heater for carbureters comprising a casing, an insulator bushing therein, a plug within the bushing, a tubing carried by the casing and closed at one end, the inner end of said plug having a terminal opening and a transverse opening communicating therewith, a resistance wire having one end received in said terminal opening, a pin in the transverse opening for retaining the same in position, the other end of the wire being connected to the closed end of the tubing, and protecting means for the wire for spacing the same from the tubing.

3. A heater for carbureters comprising a casing, an insulator bushing therein, a plug within the bushing, a tubing carried by the casing and closed at one end, a resistance wire connected at one end to said plug, means for attaching the other end of the wire to the closed end of the tubing, and means carried by the wire to hold the same spaced from the tubing.

4. A heater for carbureters comprising a

- casing, an insulator bushing therein, a plug within the bushing, a tubing carried by the casing and closed at one end, the said casing and bushing having registering slots therein, means positioned in the registered slots to prevent accidental withdrawal of the bushing, and a resistance element carried by the plug. 5. A heater for carbureters comprising a casing, an insulator bushing therein, a plug within the bushing, a tubing carried by the casing and closed at one end, and a resistance wire within the tube and connected to the closed end thereof and to said plug. 10. 6. A heater for carbureters comprising a casing, an insulator bushing therein, a plug within the bushing, a tubing carried by the casing and closed at one end, a resistance wire within the tube and connected to the closed end thereof and to said plug, and means carried by the wire to hold the same spaced from the tubing. 15. 7. A heater comprising a casing, an insulator bushing therein, a plug within the bushing, a tube carried by the casing, a resistance wire extending through the tube and connected at one end to said plug, a closure plug for the open end of the tube having an opening therein for the reception of the resistance wire, and means received in said opening for retaining the resistance wire in position. 20. 8. A heater comprising a casing, an insulator bushing therein, a plug within the bushing, a tube carried by the casing, a resistance wire extending through the tube and connected at one end to said plug, a closure plug for the open end of the tube having an opening therein for the reception of the resistance wire, and a wedge-pin received in said opening to engage the end of the resistance wire frictionally to hold the same in position. 25. 30. 35. 40.

In testimony whereof we affix our signatures.

OLIVER P. STRICKLER.
BURDETTE C. LEWIS.
